ROTARY DRIVE WHEEL TYPE CAN
OPENER

Robert E. McLean, Fort Benning, Ga.

Application February 12, 1947, Serial No. 728,064

8 Claims. (Cl. 30—15)

1

This invention relates generally to the class of cutlery and is directed particularly to improvements in can openers of the rotary drive wheel type.

An object of the present invention is to provide a can opener having a single operating handle by means of which clockwise rotation thereof causes a cutter to puncture the end of the can to which the device is applied, to hold the device and the can in operative rotation and cut the end out of the can, and subsequent counter-clockwise rotation of the said single operating handle functioning to release the can from the device, a particular feature of the present invention residing in a novel thrust mechanism operatively coupled with the can rim engaging driving wheel whereby rotation of said wheel imparts rotation to an element of the thrust means to effect a smooth, positive and strong movement of the drive wheel and the can engaged therewith, relative to a fixed cutter.

Another object of the present invention is to provide in a rotary drive wheel can opener, a novel thrust mechanism whereby the can rim engaging rotary drive wheel has movement relative to a fixed cutter and has the rim engaging piece thereof operatively coupled with a piece of a thrust gear which is adapted for movement transversely of the line of movement of the driving wheel or gear whereby rotation of an operating handle for the driving wheel effects movement of the thrust gear to a position under the driving wheel to force the latter toward the fixed cutter and counter-clockwise movement of the operating handle shifts the thrust gear to one side to permit the driving wheel to move away from the fixed cutter.

Still another object of the invention is to provide a rotary drive wheel can opener of the character above described, wherein there is provided a horizontally movable rack unit with which the thrust gear operatively engages when the driving wheel operating handle is turned counter-clockwise, whereby lateral shifting of the thrust gear is effected with a minimum of friction and a minimum of effort, the said rack member having a resilient means associated therewith for normally urging it to a position where an operative coupling will be established between the rack and the thrust gear promptly upon counter-clockwise rotation of the operating handle.

Still another object of the invention is to provide a can opener of the character stated having a thrust mechanism for effecting the functioning of the can that operates with a minimum

2

of effort on the part of the operator by reason of the great leverage afforded and the particular construction whereby all thrust parts are positioned in the same plane.

Still another object of the invention is to provide a can opener of the character stated, wherein a bearing which takes the downward thrust imposed upon the can driving wheel, is positioned in approximately the same plane as the point of thrust on the can driving wheel.

A still further object of the invention is to provide a can opener of the character stated, which is of comparatively small size and which can be economically produced.

15 The invention will be best understood from a consideration of the following detailed description taken in connection with the accompanying drawings forming a part of the specification, with the understanding, however, that the invention 20 is not confined to a strict conformity with the showing of the drawings but may be changed or modified so long as such changes or modifications mark no material departure from the salient features of the invention as expressed in the appended claims.

In the drawings:

Figure 1 is a view in elevation of the outer or right hand side of a can opener constructed in accordance with the present invention.

30 Figure 2 is a view in elevation of the inner or left hand side of the same.

Figure 3 is a view in top plan of the opener.

Figure 4 is a view in front elevation of the opener.

35 Figure 5 is a vertical section taken substantially on the line 5—5 of Figure 4.

Figure 6 is a vertical section taken substantially on the line 6—6 of Figure 5.

40 Figure 7 is a sectional view corresponding to the lower part of Figure 5 but showing the thrust gear in rearwardly shifted inoperative position.

Figure 8 is a horizontal section taken substantially on the line 8—8 of Figure 5.

45 Figure 9 is a view in elevation of the right hand side of a modified embodiment in which the device is secured to a supporting arm attached to a wall or other supporting structure.

Referring now more particularly to the drawings the numeral 10, in Figure 1 to 8 inclusive, 50 generally designate a body plate of rectangular form, which is vertically disposed in the use of the device. This body plate at its lower edge is connected by the narrow laterally extending flange or web portion 11, with the bottom edge of an upstanding portion 12, which upstanding portion

has a vertically directed part 13 of reduced width which functions as a can guide to maintain the lateral portion of a can a predetermined distance from the lower edge of the hereinafter described can driving wheel. As shown most clearly in Figures 4, 6 and 8 the parts 12 and 13 are in face parallel relation with the plate body 10 and have a further specific function as herein-after described.

Formed thru the plate slightly forwardly of the vertical center, is an elliptical slot or opening 14. This slot has mounted therein for rotary movement and for a movement longitudinally of the slot and, accordingly, vertically of the body plate, a journal 15 through which extends a shaft 16 which forms an integral part of a thumb and finger crank 17.

Upon the left or inner side of body plate 10 the shaft 16 has mounted thereon and secured thereto, the can rim engaging toothed driving wheel 18. This wheel has pointed teeth 19 which perform a double function in that they engage under the flange or rim of the can and they also engage teeth of a thrust gear, hereinafter described.

Upon the right hand or outer side of the body plate 10 and opposite from the toothed driving wheel 18, is positioned a thrust link 20. This link has in one end, a bearing opening 21 in which is positioned the journal 22. This journal 22 is of the same diameter as the journal 15 and is positioned directly thereagainst and, as will be readily apparent, the journals 15 and 22 may be formed as a single unit if desired. Accordingly, the shaft 16 passes thru the journal 22 and such journal is maintained in position against a tendency to move outwardly on the shaft 16, by the collar 23 which is traversed by and fixed to the shaft and maintained in position by engagement against the adjacent side of the thumb and finger crank 17.

As is readily apparent the slotted end of the link 20 is positioned across the elliptical opening 14 and the link extends downwardly across a transverse bearing opening 24 formed thru the body plate below the elliptical opening 14. As shown most clearly in Figure 1, one end only of the opening 24, is disposed directly below the elliptical opening 14, the major portion of the opening 24 extending rearwardly across the longitudinal center of the plate. At the end of the opening 24 which is directly below the elliptical opening 14, the opening 24 has the lower edge thereof elevated slightly to provide a journal seat 25.

Disposed in and extending thru the opening 24 is the journal 26 which has secured thereon, for rotation, on the left hand or inner side of the body plate 10, the thrust gear 27, the teeth 28 of which mesh with the teeth of the driving wheel 18.

The forward end of the transverse opening 24 is of a width between the top edge and the seat 25, to snugly receive the trunnion 26 and when the trunnion is in position in this end of the opening, upon the seat 25, its center is directly in line longitudinally of the plate with the rotary center of the driving wheel 18 and the diameter of the thrust gear 27 is such that when the journal 26 is in this last named position the driving wheel will be elevated to a position where the journal 15 will be just slightly short of the extreme upward position to which it might be moved in the elliptical opening 14. Also, when the centers of the driving wheel and

thrust gear are directly in vertical alignment, the thrust link 20 will be vertically disposed as will be readily apparent. When the thrust gear 27 is moved transversely of the plate or rearwardly where the trunnion 26 is located at the rear end of the slot 24, the thrust link 20 will assume a position oblique to the length of the plate as shown in Figure 1 and the driving wheel will ride down on the front side of the thrust gear as shown in Figures 2 and 7. As shown in Figure 6 the outer end of the journal 26 is of reduced diameter and is fixed in a suitable opening in the lower end of the thrust link 20, as indicated at 29, whereby the foregoing action is obtained.

Disposed between the lower part of the body plate 10 and the upturned portion 12, and slidably supported upon the connecting intermediate portion 11, is slidably mounted the rack plate 30. The rear end portion of the plate 30 has formed along the top edge the upstanding teeth 31 which are at a proper elevation for engagement by the teeth of the thrust gear 27 when rotation is given the latter by counter-clockwise rotation of the thumb and finger crank 17. This toothed portion 31 of the rack plate extends thru substantially half the length of the plate at the rear and the portion of the plate forwardly of the teeth is of reduced height so that when the gear 27 is rotated by clockwise turning of the thumb and finger crank so as to shift the thrust gear to its forward position as shown in Figure 5, the teeth of the thrust gear will disengage from the rack teeth and continued rotation can be given to the thrust gear and to the can driving wheel.

The plate or rack unit 30 has formed therethru the two longitudinal slots 32 and 33. The slot 32 is here shown as being in the rear portion of the plate and there extends thru each of these slots, a movement limiting pin 34 which is in the form of a rivet extending thru and connecting lower portions of the plates 10 and 12.

The slot 32 of the rack plate is of substantial length and there is housed therein and interposed between the adjacent pin 34 and the forward end of the slot, the spring unit 35 which constantly tends to urge the rack plate to the limit of its movement forwardly.

On the left hand side of the body plate 10 there is fixed at the top end of the plate the knife head 36. This head is in the form of an open frame having a straight side bar portion 37 connected with the right angularly extending end portions 38, each of which terminates in the inwardly turned foot portions 39 which bear against the inner side of the body plate and are secured thereto by the rivets 40.

Disposed against the inner side of the side portion 37 of the head unit, is a knife or cutter 41 which is secured in place by the screws 42. The lower end of this cutter extends below the part 37 to which it is attached and across and in spaced relation with the inner side face of the can driving wheel as clearly shown in Figures 4 and 6. The lower end of the knife 41 is pointed as indicated at 43 to facilitate proper penetration of the can head when the latter is forced against the knife.

Figure 9 illustrates the application of the present cutter or opener to a fixed arm which is designed to be secured by a suitable bracket, not shown, to any satisfactory support such as the wall or the like.

In this modified embodiment the supporting

arm is generally designated 44 and the forward end portion is of reduced width as indicated at 45, to extend across the right hand or outer side of the body plate of the opener, which plate is here generally designated 10'.

The rivets by means of which the cutter head is secured to the body plate are employed for securing the body plate to the arm, such rivets being designated 48' and in addition to these there is employed a third rivet designated 49' which is passed through the supporting arm 44 and to the body plate 10' just above the toothed thrust wheel 27' and rearwardly of the elliptical body plate opening 14'.

The construction of the arm supported embodiment of the invention is the same as that first described and shown in Figures 1 to 8 inclusive with the exception that the shaft 16', instead of being formed as an integral part of a thumb and finger crank, terminates in and is secured to one end of a relatively long hand crank 46. The outer or free end of this hand crank is equipped with a suitable means, not shown, for grasping the crank such, for example, as a knob.

In the use of the present opener, reference being made particularly to the embodiment shown in Figures 1 to 8, although it will be understood that the same explanation applies to the bracket supported embodiment shown in Figure 9, if the supporting thrust gear 27 is not in extreme rearward position as it is shown in Figures 2 and 7, the operating handle 17 is rotated counter-clockwise until the thrust gear is in such position. The can driving wheel 18 will then be in its lowest position.

The device is then placed on the can with its cutter blade 41 over the rim or flange of the can. The operating handle 17 is then rotated clockwise until the end of the can is cut out. Reverse or counter-clockwise rotation of the operating handle 17 then releases the can from the device and prepares it for reception of the next can.

The upper edge of the slot 24, through the journal rivet 26, maintains the teeth of the supporting thrust gear 27 in mesh with the teeth 31 of the rack 30 at all times except when the supporting thrust gear 27 is in the position illustrated in Figure 5 and is rotated clockwise as viewed in that figure. The spring 35 urges the rack 30 forwardly against the pins 34, the forward pin limiting the movement of the rack forwardly, rearwardly and upwardly as shown. The rear pin limits the movement of the rack forwardly and upwardly.

The link 20 maintains the axis of the supporting thrust gear 27 a predetermined distance from the axis of the can driving wheel 18 at all times to keep the teeth of the supporting thrust gear 27 properly meshed with the teeth of the can driving wheel 18 during the operation of the opener and as the can is being punctured and also during the operation of cutting the end out of the can, the can driving wheel 18 seats on the supporting thrust gear 27.

The opening 21 formed in the upper end of the link 20 for the journal 22, is slightly elliptical in order that the journal 22 will never bear downwardly on the link and thus interfere with the can driving wheel 18 properly seating on the supporting thrust gear 27.

The lower edge of the slot 24, except the seat portion 25, is sufficiently below the journal rivet 26 that it will never interfere with the supporting thrust gear 27 seating on the teeth of the rack 75

30. The teeth of the can driving wheel 18 would preferably be slightly longer than those of the supporting thrust gear 27 in order that the portion of the teeth of the can driving wheel 18 engaging the under edge of the rim or flange of the can, would not be in engagement with the teeth of the supporting thrust gear 14.

During the operation of opening a can, clockwise rotation of the operating handle 17 will first cause the can driving wheel 18 to rotate the supporting thrust gear 27 counter-clockwise. As the supporting thrust gear 27 rotates counter-clockwise, it moves forwardly on the rack 30 from the position shown in Figure 2. In effect, the can driving wheel 18 seats on the rack 30 through the supporting thrust gear 27. As the supporting thrust gear 27 is rotated further forwardly, the can driving wheel 18 is forced upwardly and, inasmuch as the inner ends of its teeth are under the rim or flange of the can, the cutter 41 is forced downwardly to puncture the end of the can in an obvious manner. When the supporting thrust gear 27 arrives near the forward end of the slot 24 it fulcrums from the forward tooth of the rack 30 until the journal rivet 26 seats on the seat 25 provided therefor. Also, further forward movement of the journal rivet 26 is prevented by the forward end of the slot 24. As the supporting thrust gear 27 is rotated further clockwise as viewed in Figure 5, it moves the rack 30 rearwardly, against the comparatively light tension of the spring 35, in an obvious manner, the forward tooth of the rack 30 racheting with the teeth of the supporting thrust gear 27. When the journal rivet 26 arrives on the seat 25, the supporting thrust gear 27 is then supported for rotation on the said journal rivet 26. Inasmuch as the spring 35 urges the rack 30 to the position illustrated in Figure 5 at all times, counter-clockwise rotation of the operating handle 17 will cause the supporting thrust gear 27 to move rearwardly, fulcruming on the forward tooth of the rack 30 to rise slightly and lifting the journal rivet 26 from its seat 25. The thumb and finger crank or handle 17 may then be further rotated counter-clockwise until the supporting thrust gear 27 arrives to the position which it is shown in Figure 2, at which time the can driving wheel 18 will again be in its lowest position.

50. It will be seen that the rack 30, the supporting thrust gear 27, the portion of the journal rivet 26 upon which the supporting thrust gear 27 is supported for rotation when not supported on the rack 30, and the can driving wheel 18, are all in the same plane, which materially reduces operating friction and thereby promotes the ease of operation.

If desired, the teeth of the can driving wheel 18, the teeth of the cooperating supporting thrust gear 27, and the teeth of the cooperating rack 30, may be formed in any other size and/or contour desired.

While the foregoing description of the operation has been directed particularly to the structure shown in Figures 1 to 8 inclusive it will be obvious how this description applies also to the structure shown in Figure 9.

The portion 37 of the supporting frame 36 has sufficient resiliency to permit the cutter blade 41 to be forced away from the can driving wheel 18, laterally, a predetermined amount when necessary, such as when passing the seam of the can.

If desired, a separate part can be used for the can driving wheel and secured on the same axis 75 as the illustrated can driving wheel 18 but to

the left thereof, in which case the part presently illustrated as the can driving wheel would function as a gear. In such construction, the frame supporting the cutter blade 41 would, obviously, be extended to the left as required.

Also, if desired, the journal rivet 26 may be formed with a head for retaining the supporting thrust gear 27. When so formed, the can guard 13 would either be terminated below the head of such alternately formed journal rivet or extended upwardly and provided with a suitable slot in which the head would lie.

I claim:

1. A rotary drive wheel type can opener comprising a body plate designed to be positioned vertically for use and having an elongated opening extending longitudinally therein, a journal mounted in said opening for rotation and shifting movement between raised and lowered positions therein, a toothed can rim engaging driving wheel secured on said journal, a thrust gear having toothed connection with said wheel, means supporting the gear for movement in a path extending across the line of movement of the wheel carrying journal in said opening, said gear when at the limit of its movement in one direction having its rotary center in line longitudinally of the plate with the center of the driving wheel and supporting the wheel and journal in raised position, a cutter supported by the body plate for coaction with the wheel when the latter is in said raised position, and means for rotating the wheel.

2. A rotary drive wheel type can opener of the character stated in claim 1, wherein the said means for supporting the gear for movement comprises an elongated opening formed in the body plate, and a journal mounted in the opening for rotary movement and for movement longitudinally of the opening.

3. A rotary drive wheel type can opener of the character stated in claim 1, wherein the said means for supporting the gear for movement comprises an elongated slot formed in and extending in a direction transversely of the plate, a journal carrying the gear and extending through said slot and adapted for rotation and movement longitudinally therein, and a link operatively coupling the last named journal and said driving wheel and disposed upon the opposite side of the body plate from the driving wheel and gear.

4. A rotary drive wheel type can opener of the character stated in claim 1, with a toothed rack supported by the body plate beneath and in toothed connection with said thrust gear when the thrust gear is away from the said limit of its movement in one direction, said toothed rack being positioned and adapted to have the thrust gear run out of toothed connection therewith when the gear is at the limit of its movement in the said one direction.

5. A rotary drive wheel type can opener of the character stated in claim 1, wherein the said means supporting the gear for movement comprises an elongated slot formed through the body plate at an elevation below the said elongated opening and terminating at one end directly in line longitudinally of the plate with the elongated opening, a journal mounted in said slot and sup-

porting said gear, the slot at the said one end being of a height substantially equal to the diameter of said last journal and of increased diameter toward its other end, a link operatively coupling said journals together and positioned on the opposite side of the body plate from the wheel and gear, and said link having slight longitudinal free movement on the first mentioned journal.

6. A rotary drive wheel type can opener comprising a substantially rectangular plate designed to be vertically positioned for use, the plate having an elongated opening formed therein and having its long axis longitudinally of the plate, a cutting element rigidly supported in spaced parallel relation with one side face of the plate, a journal in said elongated opening and adapted to move vertically therein and to rotate therein, a shaft extending through the journal, a toothed driving wheel supported upon the shaft against the said one side of the body plate and in a plane between the body plate and the cutting element, means connected with the shaft on the other side of the body plate for rotating the shaft, a slot formed through the body plate in a transverse direction and in a plane below the elongated opening, one end of the slot being in line longitudinally of the plate with the elongated opening, a journal extending through the slot and adapted to move longitudinally thereof and to rotate therein, a toothed thrust gear carried by the journal against the said one side face of the plate and having toothed connection with the driving wheel, said last mentioned journal when in the said one end of the slot positioning the thrust gear directly beneath the toothed driving wheel and maintaining the toothed driving wheel in raised position for coaction with said cutter, and a link connecting said shaft with the second mentioned journal and disposed against the said opposite side face of the body plate.

7. A rotary drive wheel type can opener of the character stated in claim 6, with a toothed rack supported beneath the thrust gear beneath the major portion of the slot away from the said one end of the slot for toothed engagement with the teeth of the thrust gear when the second mentioned journal is moved toward the other end of the slot, said thrust gear teeth running out of engagement with the rack teeth when the thrust gear is in position to maintain the driving wheel in its raised position.

8. A rotary drive wheel type can opener of the character stated in claim 7, wherein said rack is supported for limited movement transversely of the body plate, and spring means normally urging movement of the rack in a direction to facilitate engagement of the thrust gear teeth with the rack teeth upon rotation of the thrust gear in one direction.
